[57] ABSTRACT

A container with an externally threaded neck adapted to be closed by a twist-off crown. The height of the threads as measured from the upper surface of the neck is greater than one-quarter of the external diameter of the neck at the threads. The neck is provided with a ring below the threads having a diameter exceeding the external diameter of the neck at the threads by at least 10 percent. Standard bottles have external diameters equal to 25 mm, rarely greater than 26 mm; for such bottles, the ring diameter exceeds the external diameter by at least 2.5 mm. The ring protects and guides the fingers of the user when unscrewing the crown.

FIG. 8

RECEPTACLE WITH AN EXTERNALLY
THREADED NECK CLOSED BY A CROWN CORK

The present invention relates to a container with an externally-threaded neck adapted to be closed by a twist-off crown having a skirt crimped over the threads. The crown is of the type which can then be unscrewed and removed by a twisting movement in one direction and subsequently reapplied or screwed on by a twisting movement in the reverse direction.

At the present time, containers or bottles with externally-threaded necks are commercially available where the sealing is effected by crimping the skirt of a twist-off crown over the threads. These bottles have neck diameters which unexpectedly vary only very slightly from 25 mm, the value of 25 mm being rarely exceeded by more than 1 mm. However, these prior art containers have not provided ease of opening in combination with a fluid-tight seal between the crown and the bottle neck.

The most common bottle of the prior art is shown in FIG. 1. The neck of the bottle comprises three threads 1 on the side of the neck having a neck diameter D_1 and an upper sealing surface 2 with a connecting radius 3 therebetween. A connecting radius 4 joins the upper surface 2 with the cylindrical internal surface having a diameter D_2 . Note that the threads begin at a distance h_1 from the upper sealing surface 2 and end at a distance h_2 . The distance h_1 is generally less than one-quarter of the neck diameter D_1 .

In order to close a neck of this kind, a crown can be crimped on to the threads as shown in FIG. 2. However, the gripping of the crown by hand is difficult since the points of the skirt teeth 5 project outwardly and may cut the fingers of the user when the crown is gripped.

In order to solve this problem, certain manufacturers have blunted the points of the teeth of the crown at the time of its manufacture. In this connection, the crown which is shown in FIG. 3 is provided with a cylindrical edge 6 instead of the points of the teeth. This solution to the problem presents other problems in manufacturing (the conventional presses for punching out the crown are no longer suitable). Furthermore, such a crown may be difficult to unscrew.

Oftentimes, at the time of crimping, the cylindrical edge 6 is bent back under the beginning of the thread located at the distance h_1 from the upper sealing surface 2. This distance h_1 is calculated by the bottle manufacturer so as to be less than or substantially equal to the height h of the crown before sealing. During sealing, the crown is deformed by the action of the crimping jaw and its total height becomes h' which is greater than h due to the bending back of the cylindrical edge 6 under the bottom of the thread. This bending back causes considerable difficulty to the user who wishes to unscrew the crown. The problem of gripping and unscrewing the crown thus remains unsolved.

The sealing ring of the crown utilized in closing the bottle of FIG. 1, can itself present a problem in removing or unscrewing the crown. The prior art sealing ring (cork or plastic) of some crowns have resulted in its compression on the upper surface 2, along the coupling radius 3, and also on the cylindrical external surface having the diameter D_1 . This in turn results in considerable friction which can prevent unscrewing by hand. Because of the difficulty in unscrewing by hand, some manufacturers have provided a kind of bottle opener in

the bottom of the bottle (serving as housing for the crown) which makes it possible to open a bottle by using another bottle. This merely avoids the unscrewing problem and does not solve the problem.

Some efforts have been directed toward reducing the friction of the crown's sealing ring so as to provide the consumer with a crown which can be removed by hand. These efforts have involved the shape of the ring as well as its composition. One prior art solution is an annular sealing ring which is compressed on the connecting radius 4, that is to say towards the interior of the neck. With this type of ring, the crown is unscrewed with relative ease, but three drawbacks remain :

1. The points on the teeth of the crown still project and may injure or cut the user.

2. The bottom of the skirt of the crown (see FIG. 4) is frequently bent back under the beginning of the thread located at a distance h_1 from the upper sealing surface. This is again due to the calculation of the distance h_1 , which is substantially equal to the height h of the crown before sealing. The result is a locking effect on the crown which tends to prevent unscrewing.

3. The sealing joint is compressed on a connecting radius with the internal cylindrical surface on the neck. 25 This part of the bottle is particularly difficult for the bottle maker to manufacture. There are therefore large tolerances on the diameter and defects, which make fluid-tight sealing doubtful. Even where the tolerances are maintained, the internal pressure existing inside the 30 closed bottle (in the case of gassy liquids) outwardly deforms the base of the crown, and this deformation increases towards the center of the crown. A sealing ring such as that which has just been considered will therefore become decompressed and the seal may be 35 broken.

FIG. 5 shows a conventional, commercially available crown which is intended to close the neck of a bottle such as that shown in FIG. 1 while eliminating the third drawback, decompression of the sealing ring. The 40 crown comprises as a sealing means an annular ring 7 surrounding a base coating 8. The ring 7 is wholly located inside a cylindrical zone which has substantially as its diameter, the neck diameter D_3 . Thus the ring 7 lies partly in the skirt-bottom connecting zone of the 45 shell and partly on the bottom of the shell. Actually, it is located at the outer limit of the shell-bottom. During sealing, this ring will become compressed on the upper surface 2, in a zone close to the connecting radius 3, and over at least part of the connecting radius 3. This 50 offers two advantages :

1. The compression zone of the ring on the bottle (towards the exterior) is a zone easy for the bottle maker to produce, and it may therefore be expected that the sealing surface has been particularly well made and within the appropriate tolerances.

2. If the internal pressure which exists in the stoppered bottle (again in the case of gassy liquids) deforms the bottom of the crown, the deformation diminishes 55 towards the exterior of the crown and the joint is not substantially de-compressed.

Fluid-tightness is thus substantially assured while the problem of friction of the ring on the glass bottle and the resultant problem of unscrewing are partly solved since the seal is only formed between a ring which rubs 60 against a small surface of the bottle. On the other hand, all the difficulties of manipulation and gripping remain ; i.e., the projection of sharp points on the crown pres-

enting a hazard to the user and the folding back of the bottom of the skirt under the bottom of the threads with the resulting locking effect.

It is therefore an object of this invention to provide a container having a neck receiving a twist-off crown which prevents injury to a user removing the crown.

It is a further object of this invention to provide a container having a neck receiving a twist-off crown which prevents locking of the crown on the neck.

It is a still further object of this invention to provide a container having a neck adapted to receive a conventional twist-off crown having minimum frictional engagement with the neck and forming a fluid-tight seal even when the crown is outwardly deformed.

In accordance with these and other objects, a bottle 15 is provided having a threaded neck adapted to receive a twist-off crown and a ring located beneath the threads on the neck. The diameter of the ring is sufficiently large to guide the fingers of the user and prevent injurious contact with the crown points at the bottom of the crimped crown skirt. In this connection, the diameter of the ring may exceed the diameter of the threaded neck by 10 percent. In particular for conventional bottle neck diameters, which vary only very slightly from a value of 25 mm, the diameter of the ring exceeds that of the neck by at least 2.5 mm.

Such a ring thus enables the resolution of the problem of the gripping of the crown for removal by unscrewing by protecting and guiding the user's fingers.

Also in accordance with these and other objects of the invention, the threads on the neck of the bottle have sufficient height to prevent the locking of the crown on the neck when the bottom of the skirt is crimped inwardly. In this connection, the overall height of the threads may be greater than one-quarter of the neck diameter.

The further features and advantages of the present invention will further be brought out in the description which follows below wherein reference is made to the accompanying drawings in which :

FIG. 1 is an elevational view of the neck of a prior art bottle;

FIG. 2 shows the neck of FIG. 1 in combination with a conventional twist-off crown;

FIG. 3 is an elevational view of a conventional prior art crown;

FIG. 4 is a partially sectioned view of the crown of FIG. 3 in place on the bottle neck of FIG. 1;

FIG. 5 is a sectional view of the prior art crown of FIG. 3;

FIG. 6 is an elevational view of a bottle neck embodying the invention;

FIG. 7 shows the neck of FIG. 6 in combination with a conventional twist-off crown ;

and FIG. 8 shows the details of a bottle neck according to the invention on an enlarged scale.

In accordance with the embodiment shown in FIG. 6, the externally threaded neck forming the subject of the present invention comprises four threads 9, an upper sealing surface 10 defined by a neck diameter D_3 and a connecting radius 11. The connection between the upper sealing surface and cylindrical internal surface may be of any kind which gives the bottle manufacturer full liberty in the construction of the cylindrical internal surface.

The sealing surface of a neck of this kind is formed by the portion of the upper surface 10 close to the cou-

pling radius 11, and also by a portion of the coupling radius. It may be advantageous to utilize a very small coupling radius (close to a right angle) which has the effect of better localizing the sealing surface (solely on the upper surface 10), and thus of better controlling the unscrewing force if this should prove necessary.

In accordance with one important aspect of the invention, the threads begin at a distance h_3 from the upper surface 10. This distance is in fact calculated so as to be greater than the height h of the crown of fact the diameter D_5 shown in FIG. 7, which is a precise indication of the degree of closure of the crown on the threads. This diameter D_5 is generally determined by the crown manufacturer.

As mentioned above, the diameter D_4 of the ring 12 of the invention is equal to or greater than the crimping diameter D_5 of the crown. This diameter D_5 is a function of the diameter D_3 of the orifice (not shown) of FIG. 6 and generally, in the range of neck diameters approximately equal to 25 mm, we have :

$$D_5 = D_3 + D_3/10$$

The ring of the present invention thus has its diameter defined under these conditions by the relation :

$$D_4 \geq D_3 + D_3/10$$

In accordance with another important aspect of the invention, the neck as shown in FIG. 6 is provided with a ring 12 having a diameter D_4 . This ring prevents the user from hurting his fingers at the time of unscrewing the capsule as shown in FIG. 7. Note that the points of the teeth 5 while projecting, cannot injuriously contact the user's fingers 13, since the inward movement of the fingers is limited by the ring 12 having a diameter D_4 greater than the diameter of the crown D_5 . The user's principal contact is with the ring 12 having a smooth surface and not the projecting points 5 of the crown.

In the crown industry, a closure is characterized by a magnitude known as the "crimping size." This is in FIG. 5 (or of FIG. 3) before closing so as to remain greater than the height h' which this crown may have after crimping. The conditions are therefore :

$$h_3 > h' > h$$

It is thus readily understood that the base of the skirt of the crown can no longer be bent back under the beginning of the thread and the known locking effect is thereby eliminated.

It has previously been seen that the distance h_1 utilized on the neck of FIG. 1 was in general less than one-quarter of D_1 , 6.25 mm for neck diameters close to 25 mm. In the case of the embodiment of the present invention, the distance h_3 , thus becomes greater than one-quarter of the diameter D_3 in the aforesaid range.

The position of the ring with respect to the bottom of the crown must enable the user's fingers to be guided without interfering with the crown. It has been found that the distance from the upper sealing surface to the top of the ring must not exceed one-quarter of the neck diameter by more than approximately 50 percent. Tests have shown that when this limit is exceeded, the beneficial result sought after is no longer present. The position of the ring will be further described relative to FIG. 8.

The neck diameter D_3 of the cylindrical surface 17 is the external diameter at the free end of the neck. The cylindrical surface 17 extends axially to the position A

at which the threads begin. At this point and extending in the opposite direction begins a zone of widening 14, which connects the cylindrical surface to the ring.

The term "top of the ring" refers to the axial position E, where the diameter of the neck has a certain minimum value D_4 . Below this point the ring has a cylindrical or slightly truncated conical surface terminating in a narrowing zone 16. The diameter of the neck is therefore a limited axial distance equal to that of said neck diameter.

The term "bottom of the ring" refers to the axial position F where the diameter becomes less than the said value D_4 .

According to this definition, the width of the ring ought not to be more than 50 percent greater than one-quarter of the diameter D_3 . Further, the distance H_5 from the upper-sealing surface to the bottom of the ring will be advantageously limited to value less than twice the height h_3 of the threaded portion such that the width ($H_5 - h_4$) of the ring will remain in general less than half the height h_3 .

As has already been described, fluid-tightness is assured by the annular ring of FIG. 5. A ring of this kind is compressed against the upper sealing surface of the neck and to some extent against the connecting radius 11. The choice of the nature and the weight of the sealing material which constitutes this ring makes it possible to determine the unscrewing force required with an accuracy which will increase as the connecting radius 11 is decreased. Experience has shown that the connecting radius ought not to be greater than one millimeter in order that the objects according to the invention be satisfied.

The foregoing considerations apply to common bottles the necks of which have, as noted above, free end diameters close to 25 mm, the difference from this value rarely exceeding 1 mm. However, it now appears that there is a certain tendency towards neck diameters of 30 mm or more. Research has shown that the dimensions set forth according to the invention for a range of neck diameters which differ only very slightly from 25 mm remain valid for the now proposed neck diameters.

According to a further aspect of the invention, the limits hereabove defined for the usual 25 mm range will be advantageously also adopted in case of neck diameters which are substantially outside said range. This will be the case as well for the height of the threads measured from the upper sealing surface of the neck as for the guiding radial protusion formed by the ring and for the axial position of said ring. One is thus led to adopt for the diameter D_4 of the ring a minimum value which exceeds the neck diameter D_3 by at least one-tenth of the 25 mm, that is 2.5 mm. In other words, this arrangement assures a guiding ring surface 15 which protrudes over the cylindrical surface 17 of the bottle neck for at least 1.25 mm.

The height h_3 of the threaded portion of the bottle neck will be in any case greater than one-quarter of 25 mm, that is 6.25 mm.

The distance h_4 from the upper sealing surface to the top of the ring, which of course forms an upper limit for h_3 , ought not to exceed by more than 50 percent the aforesaid limit of 6.25 mm.

Finally, the distance h_5 from the upper sealing surface to the bottom of the ring should advantageously be held to values less than twice the distance h_3 such that the width ($H_5 - h_4$) of the ring will remain as a rule less

than half of the distance h_3 . A perfectly satisfactory guiding effect is thus obtained with a ring width in the order of 3 mm.

In the appending claims the free end diameter D_3 of the neck is designated by "neck diameter."

What is claimed is:

1. A bottle adapted to be closed by a twist-off crown and comprising an externally threaded neck having a plurality of threads and a radially outwardly-extending ring located beneath said threads, said ring having a diameter at least equal to maximum diameter of a crown crimped on to said neck so as to prevent injurious contact between the fingers of a user and the edge of the crown skirt.

15 2. The bottle of claim 1 wherein said neck includes an upper sealing surface adapted to be engaged by a crown, the height of said threads measured to the top of said neck being at least equal to the height of a crown crimped on to said neck.

20 3. The bottle of claim 2 in combination with a twist-off crown having a maximum diameter not greater than said ring and a height after crimping on to said neck not greater than said height of said threads.

25 4. The bottle of claim 3 wherein said neck includes an upper sealing surface at said top thereof, a side surface carrying said threads, and a connecting radius therebetween, said crown having a sealing ring compressed substantially only against said upper sealing surface and said connecting radius.

30 5. The container of claim 1 wherein said neck includes an upper sealing surface and the height of said threads as measured from said upper sealing surface of the neck is greater than one-quarter of the neck diameter.

35 6. The container of claim 1 wherein said neck includes an upper sealing surface and the distance from said upper sealing surface to the top of the ring is not greater than 1 1/2 times the height of said threads.

40 7. The container of claim 1 wherein said neck includes an upper sealing surface, a side surface carrying said threads, and a connecting radius therebetween, said connecting radius being not greater than one millimeter.

45 8. The container of claim 7 in combination with a twist-off crown.

40 9. The combination of claim 8 wherein said crown comprises a sealing ring located substantially inside a cylindrical zone of said crown having a diameter substantially equal to the external diameter of said side surface and adapted to be compressed substantially only against said upper sealing surface and said connecting radius.

50 10. The container of claim 1 wherein said threads consist of four.

55 11. The container of claim 1 wherein said neck includes an upper sealing surface and the height of said threads as measured from said upper sealing surface is greater than 6.25 mm.

60 12. The container of claim 11 wherein the distance from upper sealing surface to the top of the ring is not greater than 1 1/2 times 6.25 mm.

65 13. The container of claim 11 wherein the distance from said upper sealing surface to the bottom of the ring is not greater than twice said height of the threads.

14. The container of claim 11 wherein the width of the ring is less than half the height of said threads.

15. The container of claim 11 in combination with a twist-off crown.
